United States Patent Office

Des. 211,883
Patented Aug. 6, 1968

211,883

VASE

Charles H. McCrea, Belmont, Calif., assignor to Plastic Productions Company, Redwood City, Calif., a corporation of California

Filed Sept. 27, 1967, Ser. No. 8,751

Term of patent 14 years

(Cl. D29—28)

FIG. 1 is a side perspective view of a vase showing my new design, the sides opposite thereto being similar in appearance;

FIG. 2 is a top plan view thereof on reduced scale;

FIG. 3 is a side elevational view; and

FIG. 4 is a bottom plan view thereof on reduced scale.

I claim:

The ornamental design for a vase, as shown and described.
